UNITED STATES PATENT OFFICE.

GEORGE W. BROWNELL, OF ST. ALBANS, VERMONT.

AUTOMATIC TRAIN-STOPPING MECHANISM.

1,140,109.

Specification of Letters Patent.

Patented May 18, 1915.

Application filed December 31, 1913, Serial No. 809,779. Renewed March 29, 1915. Serial No. 17,894.

To all whom it may concern:

Be it known that I, GEORGE W. BROWNELL, a citizen of the United States of America, residing at St. Albans, in the county of 5 Franklin and State of Vermont, have invented a new and useful Automatic Train-Stopping Mechanism for Railroads, of which the following is a specification.

My invention relates to automatic train-stopping mechanisms in which means are provided for operating the air-brakes of a locomotive and train automatically when the danger signal is set; and the objects of 10 my invention are: 1st. To provide automatic means for the gradual stopping of a train by the gradual and easy operation of the brakes in one or several stages, by one or several successive applications of the air-brakes on the train, without the act of the 15 engineer. 2nd. To provide means whereby the setting of a danger signal will automatically set the brake devices for action, by the train passing a predetermined point. 20 3rd. To provide means whereby the engineer may at will resume control of the train and release the automatic brake device or apply the brakes himself independent of the automatic device. 4th. To provide means for 25 accomplishing all the objects herein which 30 will act efficiently as proposed in all conditions of weather and of track, all swaying of the engine or train, all movements of the engine forward or backward, or when more engines than one are in the train, so that 35 both engines or either may be set to respond to the danger signal, or either may be cut out, and will not endanger the engineer or operatives, or passengers, or those who may be on or near the track. 5th. To provide 40 means for accomplishing the foregoing objects which are simple, durable, effective, and of low cost, which will operate upon the train line air-pipe without interfering with the ordinary management of the brake 45 system by the engineer.

Other objects will appear from the hereinafter description.

I attain these objects by the mechanism illustrated in the accompanying drawings, 50 in which—

Figure 1 is a side elevation of a part of a locomotive, including a part of the frame adjacent to the cab, a driving wheel, and

a view of my improved brake stop mechanism, with its trip and track detent, and 55 the essential parts of the pipe connection. Fig. 2 is a rear view elevation of the trip and track detent at the moment of being actuated. Fig. 3 is an enlarged view, partly in cross-section, of the cylinders operating 60 the release mechanism of the compressed air in the train pipe, and a side view of the connected valve chamber controlling the compressed air, which works at operating the cylinder. Fig. 4 is a vertical section of the 65 valve chamber of Fig. 3; Fig. 5 is an outside perspective view of the same valve chamber showing the ends and pivots of the levers which work the same. Fig. 6 is a cross-section of the valve chamber of Fig. 70 4; on the line $x-x$.

A is a part of the frame of a locomotive at one of the driving wheels, carrying the trip which starts the automatic train-stopping mechanism.

75

B is the track detent, located midway between the rails, and consisting preferably of a long strip which may be raised in the middle by the arm b, by a chain of rods and levers not shown, by connecting the 80 same with the lever of a signal tower of a railroad which sets the semaphores controlling the speed and stops of trains; and this track detent B when set for operating the train-stopping mechanism provides a 85 slightly inclined path in either direction for the trip.

C is the valve chamber containing the piston c which controls the compressed air which operates the piston D in the cylinder E, and the piston rod F carrying the fixed collar G, and the enlarged parts H and H'.

I is a compressed air cylinder, the air from which is controlled by a stop-cock i.

95

K is the train pipe carrying compressed air for operating the brake in well known ways not necessary to describe, by releasing the pressure in part for the application of the brakes.

100

L is an air chamber connected with the train-pipe K and containing therefor compressed air, which may be gradually and intermittently released through the enlarged opening G' whenever the collar G moves 105 away from the said opening. The opening

G' is larger than the piston F, but of the same size as the enlarged portions H and H', which makes a sliding fit in the opening G'. The gradually repeated, intermittent application of the brakes is effected by one movement of the piston D, the piston-rod F bearing the collar G, and the enlargements H and H'. Traveling to the right when the collar G moves away from the opening G' air escapes from the chamber L and from the train-pipe K, applying gradually the brakes until the enlargement H on the piston F reaches the opening G' and closes it. Passing through this opening, air is again released from the chamber L, while the piston-rod between the enlargements H and H' is traversing the opening G' and is again stopped by the enlargement H', in turn reaching and closing the opening G'.

M is a spring of sufficient tension to move the piston-rod F and piston D to the left when the air pressure from the tank I through the valve chamber C is released.

The trip will be readily understood from Figs. 1 and 2, but I will give the following details: N is a roller which is idle in all running conditions except when it encounters the track detent B, when the latter is raised. O is a forked rod carrying the roller N, and the slide P in the guide Q. 1, 2, 3 and 4 are braces holding the guide Q in position, and attaching the trip to the frame A. R is a lever pivoted to a fulcrum, r, and to the rod O at r'. At r'' it is pivoted to the upright S, which extends into the cab of the engine in a place convenient to the hand of the engineer. Passing through the guide Q', it actuates by the collars s and s' the levers T and T', which in turn actuate the valve stems U and U' simultaneously, thus opening the valve C and closing the valve c' by a one movement of the upright S. V is a catch which engages a notch v in the upright S, when S is raised to its position to operate the train-stopping mechanism, by the lever V', near the hand of the engineer, the catch V is withdrawn and releases the upright S, which by its weight falls to its idle position after having passed the track detent B.

W is the compressed-air pipe leading from the tank I to the valve chamber C.

Y is the pipe connection leading from the chamber C to the cylinder E.

The operation of my improved automatic train-stopping mechanism is as follows: The track detent is so connected with the levers operating the danger signal in the signal tower as to be raised in the middle, but not at either end, whenever the semaphore is set to danger. The roller N rides up on the track detent whether the engine is running forward or backward when approaching the track detent. The forked rod O, the lever R raise the rod S, so that the catch V engages

the notch v, thus holding the rod S in its 65 uppermost position after the roller N has passed the track detent B, as well as before. The movement of the upright S actuates the levers T and T' opening the valve c, and closing the valve c', by the simultaneous movement of the valve stems U and U' downward in the valve chamber C. By this movement, compressed air from the tank I through the pipe W, into the chamber C, and out through the pipe Y, into the cylinder E, moves the piston D, the piston-rod F the collar G and the enlargements H and H' slightly to the right, against the tension of the spring M, the collar G leaving its seat, thus clears the opening G', and compressed air from the chamber L in the train-pipe K rushes out, relieving gradually the pressure in the train-pipe K, and thus applying the brakes gradually. By the further progress of the piston rod F to the 85 right, the enlarged part H then fills the opening G', and interrupts the outward rush of air from the chamber L in the train-pipe K, allowing the pressures to equalize throughout the train, thus preventing the 90 application of the brakes strongly on the cars next the engine, and not at all on those on the rear end of the train. The further slow progress of the piston F to the right again opens the opening G', and more compressed air leaves the train pipe with a still stronger application of the brakes, when again the outrush of air is stopped by the enlargement H', stopping the opening G', and there the brakes remain applied until 100 the engineer releases the catch V by the hand movement of the lever V'. The fall of the upright S through the levers T and T' closes the valve c', thus simultaneously stopping the rush of compressed air from the tank I 105 through W, chamber C and valve c to the operating cylinder E, and relieving the pressure on the piston D by exhausting to the air the compressed air through the valves c', whereupon the spring M operates to move 110 the piston-rod F and the piston D to the left to its original position shown in the drawings, thus closing the opening G' by the collar G, thus allowing the train-pipe K to regain its normal pressure and release the 115 brakes.

Numerous changes in detail and in valve mechanism may be made without departing from the spirit of my invention.

What I claim as new and desire to secure 120 by Letters Patent is:

In an automatic train-stopping mechanism, a track detent, a trip, a tank containing compressed air, a piston and cylinder, a train pipe containing compressed air, means operated by said trip for admitting compressed air from the compressed-air tank to the piston, means whereby one complete continuous

movement of the piston automatically and repeatedly opens and closes the air release from the train-pipe, thereby releasing air from the train-pipe gradually and intermittently.

In witness whereof I have hereunto set my hand at the city of Boston, county of Suffolk

and State of Massachusetts, this 30th day of October, 1913.

GEORGE W. BROWNELL.

In presence of—

REGINALD B. SIMPSON,
FRED J. BUNTIN.
